RAIL JOINT

Filed Jan. 27, 1930

INVENTOR.
JOHN A. LARSON.

BY *Joseph B. Gardner*
ATTORNEY.

UNITED STATES PATENT OFFICE

JOHN A. LARSON, OF SAN JOSE, CALIFORNIA

RAIL JOINT

Application filed January 27, 1930. Serial No. 423,623.

This invention relates to improvements in rail joints and resides in the provision of a highly efficient joint which is designed to overcome many of the objections and difficulties which attend rail joining devices such as now generally employed.

An object of the invention is to provide a rail joint of the character described which will support the weight of traction vehicles 10 passing over the rail joint and maintain the rail ends level in such manner that breaking, chipping off and undue wear of the rail ends and wheels, as well as the objectionable noises and wheel bumping and hammering actions, 15 are eliminated in a particularly efficient manner.

Another object is to provide a rail joint of the character described in which the rail ends are laid upon a common bed or base plate which is designed to be supported on two ties one on each side of the joint and is provided with an integral or rigidly fixed side plate having a novel supporting engagement with the rail ends and arranged to have its upper edge disposed substantially flush with the tread surfaces of the rails whereby it will offer a smooth unbroken wheel supporting track section past the joint and insure the provision of a smooth, strong, comparatively wearproof and noiseproof joint.

A further object is to provide a rail joining device of the character described which will eliminate welding at the rail ends and provide for a saving in time, labor, material, and installation and upkeep costs owing to the elimination of breakage, chipping, undue wear and wheel hammering actions at the joint.

40 Still another is to provide a rail joint of the character described in which provision is made in a particularly efficient manner for conduits or passageways for electrical conductors and for maintaining a well lubricated joint wherein free rail movement is permitted on expansion and contraction of the rails.

The invention possesses other objects and features of advantage, some of which, with the foregoing, will be set forth in the following description of the preferred form of

the invention which is illustrated in the drawings accompanying and forming part of the specification. It is to be understood, however, that variations in the showing made by the said drawings and description may be adopted within the scope of the invention as set forth in the claims. 55

Referring to the drawing,

Figure 1 represents a side elevation of the rail joint of my invention. .

Figure 2 represents a plan view of the joint.

Figure 3 is a sectional view taken on the plane of lines 3-3 of Figure 2.

Figure 4 is a sectional view taken on the 65 plane of line 4-4 of Figure 2.

One embodiment of my invention, as illustrated in the accompanying drawing, comprises a rail joining device which generally consists of a metal bed or base plate 1, a side plate 2 preferably formed integral with the base plate, and a removable side plate 3 arranged to be bolted to the rails and other side plate and to also be locked to the base plate. Preferably these three elements of the joining device are of equal length and arranged to be supported on three ties 4, 5, 6, disposed so that there is provided a two tie support on each side of the joint of the two rails 7 and 8. By this tie support arrangement a secure and strong anchorage of the joint is insured and the rails and rail ends will be maintained level whereby swaying and bumping of traction vehicles passing over the rails is effectively obviated.

The base plate 1 is wider than and arranged to extend under the bases of the rails and may be spiked to the ties in any suitable manner. In the upper side of the base plate are grooves 10 for grease whereby the joint will be lubricated and the rails may freely move under expansion and contraction thereof. With the two rails supported on the base plate it will be seen that the ends of the rails will be maintained in proper level and aligned relation at all times. 90 95

The integral side plate 2 is so formed and fixedly joined to the base plate that there is provided a groove-like pocket 11 in which the bases of the rails snugly engage as shown ¹⁰⁰.

in Figures 3 and 4, with the side plate overlying the upper side of the said bases. More specifically, the side plate is comprised of a short upright portion 12 against the inner 5 side of which the edges of the rail bases engage, and extended from the upper end of the short upright portion 12 is an upwardly and inwardly inclined portion 14 which overlies the rail bases, whereas from the inner 10 edge of the portion 14 is an upstanding portion 15, the upper edge of which terminates in substantially flush relation to the tread surfaces of the rails. If desired, the portion 15 is formed with its thickest portion centrally 15 of its ends and opposite the rail joint and is gradually decreased in thickness towards its ends, whereby maximum strength is provided at the joint. Thus it will be seen that the wheels of rolling stock will ride on the 20 upper edge of the side plate which offers a smooth unbroken track section, supporting along and at the joints the weight of rolling stock in conjunction with the rails and thereby preventing sagging or depression of the 25 rails, and eliminating the breaking off or undue wear of the rail ends and wheels and also eliminating wheel bumping and all objectionable noises attendant on such bumping.

Additional support of the rails and added 30 joint security and strength are provided by flanges 17 and 18 which extend inwardly and laterally from the portion 15 of the side plate 2. The flange 17 engages the under sides of the heads of the rails and also the webs of 35 the rails adjacent the joint. The flange 18 is disposed in spaced relation to and below the flange 17 and engages the webs of the rails approximately midway of the upper and lower edges of said webs. Furthermore 40 the flanges 17 and 18 define passageways or conduits 19 for flexible electrical conductors not shown, but which are usually employed to electrically connect the rails at the joints thereof.

45 The removable joint plate 3 comprises an inclined base portion 20 arranged to engage upon the rail bases in a manner similarly to the portion 14 of the side plate 2. On the under side of the base portion 20 is a depending flange 21 arranged to engage between the adjacent longitudinal edges of the rail bases and an upstanding flange 22 formed on the base plate 1, whereby the plate 3 is locked against lateral displacement. Extending 50 upward from the base portion 20 of the plate 3 is a vertical portion 23 corresponding to the portion 15 of the plate 2 and provided with a laterally and inwardly extending flange 24 arranged to engage the rail head 55 in the same manner as the flange 17. Between the flange 24 and the base portion 20 the portion 23 is provided with a flange 25 similar to the one 18 and arranged to engage the rail webs at points in line with said flanges 60 65 17.

The base 20 of the side plate 3 is provided with hook portions 26 arranged to hook under the base plate between the ties. At points over the ties said base is provided with offset extensions 27 which lie upon said ties and may be secured thereto by spikes 28. This is but one form of removable side plate and serves most efficiently as a part of the rail joint. The construction of the side plate may vary when the ties are differently laid but at all events are preferably made to extend and overlie the ties and to hook under the base plate.

The plates 2 and 3 and the rails are held together as here shown by four bolts 29 passing through aligned openings in the portions 15 and 23 of the plates 2 and 3 and through the webs of the rails. The opening 30 of the plates 2 and 3 are elongated, as shown in Figure 1 whereby free movement of the rails on expansion and contraction thereof is provided for.

It will now be apparent that I have provided a rail joining means which is comparatively simple as to construction, consists of few parts, and may be readily, easily and cheaply installed or taken down, with a saving in time and labor as compared to other types of joining devices.

An important feature is the provision for supporting the rail ends on a common base plate which carries integral and removable side plates, that together with the base plate contact with, hold together and support the rails in a particularly efficient manner, and so that part of the weight of the rolling stock is placed directly on the joint means whereby to save the rail ends from damage, as hereinbefore pointed out. It is to be noted that the portions 12, 14, 15, 17 and 18 of the side plate 2, engage the rail base edges, the rail base upper sides, the sides and under faces of the rail heads, and spaced points on the rail webs, whereas the plate 3, excepting the upper edge thereof, similarly engages the rails and these arrangements insure a rigid, secure and strong rail joint in which relative depression or sagging or lateral displacement of the rail ends and the objections which follow such derangements are positively eliminated.

I claim:

1. In a rail joint, a base plate arranged to be placed under the bases of and to support rails to be joined, an integral side plate carried by said base plate and having a portion thereof overlying and engaging the upper sides of the said rail bases, and another portion arranged to extend upward along the sides of the rails with its upper edge substantially flush with the tread surface of said rails in position to be engaged by wheels of a railway vehicle passing over the joint, another rail clamping plate bolted to said integral side plate, having a portion 120 125 130

integral with the last named plate and disposed to overlie the bases of the rails and said base plate and to lie upon ties adjacent the rail joint.

5 2. In a rail joint, a base plate arranged to have the bases of rails rested and supported thereon and side plates secured to said base plate and arranged to be bolted together through and against the rails to be joined thereby, and hook portions on certain of the side plates arranged to hook over and under an edge of the base plate between the rail ties adjacent to the rail joint, and laterally extending portions on the last named plates

10 15 extending over and beyond the base plate and engaging and being spiked to said ties.

3. In a rail joint, a base plate arranged to be placed under the bases of and to support rails to be joined, an integral side plate carried by said base plate and having a portion thereof overlying and engaging the upper sides of the said rail bases, another portion arranged to extend upward along the sides of the rails with its upper edge substantially

25 flush with the tread surface of said rails in position to be engaged by wheels of a railway vehicle passing over the joint, another rail clamping plate bolted to said integral side plate, and portions on the last named side plate arranged to hook over and under the base plate, and other portions on said last named side plate arranged to extend outwardly over and beyond the base plate to rest upon rail ties adjacent the rail joint, said

30 35 last named portions being offset to define shoulders disposed to engage the adjacent edges of the rail bases.

4. In a rail joint, a base plate arranged to have the bases of the rails rested and supported thereon, side plates associated with said base plate and arranged to be bolted together through and against the rails, portions of one of said plates being bent to hook under the base plate between rail ties adjacent the joint, and members on said last named plate extending outwardly therefrom over the rail bases and base plate and lying upon said rail ties.

In testimony whereof I have hereunto set my hand at Oakland, California, this 8th day of January, 1930.

JOHN A. LARSON.
